UNITED STATES PATENT OFFICE.

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed February 18, 1924. Serial No. 693,418.

This invention relates to internal combustion engines, particularly to the cooling systems thereof. It has for one object to provide cooling apparatus which shall maintain the operating temperature of the motor cylinders more nearly uniform without unduly limiting the heat dissipating ability of the system.

Another object is to provide a cooling system for internal combustion engines in which any vapor formed in the cooling jackets shall be condensed, and loss of the cooling fluid thereby reduced.

Other objects of the invention will appear from the following description taken in connection with the drawings, which form a part of this specification, and in which:

Fig. 1 is a view, partially in section and partially in broken elevation, of the forward end of an internal combustion engine showing the application of this invention thereto;

Fig. 2 is a front elevation, partially in section, of a portion of the apparatus illustrated in Fig. 1;

Fig. 3 is a view in side elevation of the apparatus shown in Fig. 2, with portions broken away;

Fig. 4 is a longitudinal section through the pump and jacket inlet connection, taken substantially on the line 4—4 of Fig. 3, and

Fig. 5 is a diagram showing the circulation of the cooling fluid through the various portions of the system.

Most of those cooling systems for internal combustion engines which employ the circulation of water or other appropriate liquid in heat exchanging relation with the engine cylinders are either of the thermo-siphon or of the forced circulation type. In the thermo-siphon or natural system, circulation is obtained by reason of the difference in weight between the hot and cold liquid. The heat imparted to the water in the cooling jackets causes it to rise therein and it then flows through a suitable connection to the upper part of the engine radiator, wherin it is cooled. It descends by gravity through the radiator, flowing out at the bottom thereof through an appropriate connection to the cooling jacket inlet.

In this type of cooling system, a comparatively large volume of fluid is circulated at a rate which depends on the difference in temperature, and therefore varies with the heat developed. The system ordinarily insures a

more even temperature of the engine cylinders and possesses structural simplicity. However, it has the disadvantage that after the entire volume of liquid is heated to the boiling temperature the rate of circulation does not increase with further heat, and the heat absorbing ability is therefore limited.

In the forced circulation system the cooling jackets and the engine radiator are connected in series with a suitable power driven pump so that the cooling fluid is positively circulated through this system. In this arrangement a comparatively small volume of water is circulated at a relatively high speed. The rate of circulation may or may not be in proportion to the heat developed, but it is usually in proportion to engine speed and the heat dissipating ability of such systems is ordinarily greater than that of comparable thermo-siphon systems. For this reason it is the better adapted for engines which run for considerable periods at full speed.

In liquid cooling systems of all types a certain amount of the fluid is lost, caused by the formation of vapor or steam in the jackets, which vapor escapes through the vent provided at the highest point in the system, usually the upper end of the radiator.

By the present invention is provided a cooling system in which are combined the advantages of both thermo-siphon and forced circulation systems. This is obtained through an arrangement by which the circulation of liquid through the cooling jackets is maintained by the thermal effect, thus insuring uniformity of cylinder wall temperature, and the circulation through the radiator is forced, thus insuring an adequate cooling of the liquid medium. The invention also provides means by which loss of the cooling fluid caused by the escape thereof in a vaporous state at the top of the radiator, is prevented.

Referring to the drawing, at 10 is shown a portion of an internal combustion engine having the usual block of cylinders 11 in which pistons 12 are adapted to reciprocate in the ordinary manner. The pistons 12 are connected by means of rods 13 with a crank shaft 14, journaled in bearings 16 in the engine crank case 17. The engine is provided with a cam shaft 18 formed with cams 19 and actuated in any suitable manner, as by means of the chain 21 from the crank shaft 14. The cams 19 are adapted to actuate suitable valves (not shown) by means of which the admis-

sion of fuel to and the exhaust of burned gases from the engine cylinders 11 is controlled, in a manner well understood in the art to which this invention relates.

5 The cylinders 12 are surrounded by suitable spaces forming cooling jackets 22 through which a liquid is circulated to cool the engine in the usual manner. Any suitable liquid may be circulated through the 10 jackets 22, but water is preferably employed, and the cooling fluid will be hereinafter so referred to. The lower portions of the jackets 22 are connected by a suitable distributing manifold, the cover of which is 15 shown as a plate 23 removably secured to the cylinder casting as by means of the screws 24. The distributing manifold is provided near its forward end with an intake 26, which, as shown, consists of a flange connection 20 adapted for cooperation with an intake pipe 27.

Above the cooling jackets 22 is located a cooling discharge manifold 28 communicating with each of the jackets 22. The manifold 28 is preferably formed with an increasing section toward the forward end of the engine and is adapted to receive the heated water from each of the jackets 22. The forward end of the manifold 28 is provided with 30 an upwardly disposed portion forming a housing 29. This housing may be connected in any convenient manner, as by means of the hose connection 31, with the intake pipe 32 of a suitable radiator 33.

35 The radiator 33 preferably consists of an upper tank 34 and a lower tank 36 connected by a suitable cooling section 37 through which the cooling water is adapted to flow. The water conducting portion of the section 40 37 may be of any suitable structure, and preferably comprises a large number of small water passages having a large radiating surface and formed to permit of intimate contact with the atmospheric air in a manner well understood in this art.

The lower radiator tank 36 is provided with a suitable outlet 38 which is adapted for connection, as by the hose connector 39, with a distribution pipe 41. The pipe 41 is formed 50 with two branches, one of which is the jacket intake pipe 27 and the other of which constitutes a pump intake pipe 42 as clearly shown in Fig. 4.

The pipe 42 is connected, as by means of a 55 flange 43, with a suitable housing 44 formed in or secured to the engine casting. In the inlet housing 44 is suitably mounted a water pump 46 which may be of any suitable construction but which is preferably of the 60 centrifugal type, mounted on a shaft 47 which projects through a packing gland 48 in the forward wall of the housing 46 and is adapted to be driven from the engine in any convenient manner, as by means of the belt 49. The 65 structure of the pump 46 is well known in the

art to which this invention relates and further description thereof is omitted. The pipe 42 communicates with the intake passage 45 of the pump 46, and the discharge passage 51 thereof communicates by means of a suitable 70 connection 52 with the vertically arranged conduit 53, suitably secured on the side of the engine block.

The pipe 53 is provided at its upper end with a flange 54 by means of which it is connected to the housing 29 so as to register with a passage 56 formed therein. This passage 56 terminates in a nozzle 57 of any desired configuration, preferably co-axial with and upwardly disposed in the housing 29. It 75 will be apparent that the pipe 42, the housing 44, and the conduit 53 with its associated nozzle 57 constitute a by-pass for the cooling jackets 22, being in parallel therewith. It 80 will also be seen that the pipe 41 serves to 85 divide the cooling water from the radiator outlet 38, between the jackets 22 and the by-pass just mentioned.

The operation of the device will be evident. Heat is absorbed by the cooling water in the 90 jackets 22 and becoming lighter is displaced therein by cold water entering through the distributing manifold from the jacket intake 26. The heated water enters the jacket discharge manifold 28 and rises in the forward end thereof into the housing 29. At this point it meets a jet of cold water from the nozzle 57, under the pressure developed by the pump 46, which exerts an ejector action 95 thereon, condensing and cooling any vapor or steam carried by the heated water from the manifold 28. The partially cold water then rises through the connector 31 and the radiator intake 32 and enters the upper radiator tank 34. From the tank 34 the 100 water descends in the usual manner through the radiator cooling section 37 where its heat is transferred to the atmospheric air passing therethrough in the well known manner. The cold water enters the lower radiator tank 105 36 from which it flows by way of the radiator outlet 38 and the connector 39 to the distribution pipe 41, in which it is divided between the pump 46 and the jackets 22.

110 It will be seen that that portion of the cooling system which includes the jackets 22, operates on the thermo-siphon system, so that the circulation therein depends on the heat developed by the engine. This insures a more even operating temperature for the cylinders 11, as has been heretofore pointed out. On the other hand that portion of the system which includes the radiator operates on the forced feed principle, with its relatively 115 greater cooling effect, so that adequate cooling of the engine as a whole is insured.

120 It will be noticed that the pump 46 is in series with the radiator and in parallel with the jackets 22.

125 Should the engine be operated upon a 130

heavy load for a sufficient length of time to boil the water in the jackets 22, the resulting steam will be quickly and easily condensed in the housing 29 on meeting the jet of cold water from the nozzle 57. As this condensate mingles with the stream of water entering the radiator inlet 32, no loss of water will occur from this cause.

It will be understood that various forms of the invention other than those described above may be used without departing from the spirit or scope of the invention.

What is claimed is:

1. The combination with an internal combustion engine of a cooling system comprising cooling jackets, a radiator, a pump, and branched connections between the radiator outlet and the radiator inlet including the pump and said jackets in parallel.

2. The combination with an internal combustion engine of a cooling system comprising jackets, a radiator, a pump, a connection adapted to divide water from the radiator outlet between the pump and the jackets, and means connecting the pump and the jacket outlets to the radiator inlet.

3. The combination with an internal combustion engine of a cooling system comprising jackets, a radiator, a pump, and conduits having common portions from the jacket outlet and the pump outlet to the radiator inlet, and from the radiator outlet to the jacket inlet and the pump inlet.

4. The combination with an internal combustion engine of a cooling system including jackets, a radiator arranged to secure a thermally induced circulation through said jackets, and means to provide a forced circulation through the radiator, said jackets forming a by-pass for said means.

5. The combination with an internal combustion engine including cooling jackets and a radiator, of conduits connecting said jackets and radiator in series, a pump adapted to maintain a forced circulation of water through the radiator, and means connecting the pump between said conduits to form a by-pass for said jackets.

6. The combination with an internal combustion engine, of cooling jackets and a radiator connected to form a closed circulatory system, a pump connected in parallel with

said jackets adapted to maintain a forced circulation through the radiator, and a jet in the discharge from said pump adapted to exert an ejector action on the discharge from said jackets.

7. The combination with an internal combustion engine including cooling jackets and a radiator connected to form a closed circulatory system, of a pump adapted to draw liquid from the radiator outlet and to discharge it into the jacket outlet only to exert an ejector action thereon.

8. The combination with an internal combustion engine of a water cooling system having a cylinder jacket, a housing on the engine communicating with the jacket outlet, a radiator, a connection from the housing to the radiator inlet, and means to supply a jet of cold water under pressure to said housing.

9. The combination with an internal combustion engine of a water cooling system having cylinder jackets and a radiator, a connection from the jacket outlet to the radiator inlet, a connection from the radiator outlet to the jacket inlet, a pump adapted to withdraw water from the last named connection, and a nozzle in the first named connection supplied by said pump.

10. The combination with an internal combustion engine of a cooling system having cooling jackets and a radiator, a housing on the engine communicating with the jacket outlet and connected to the radiator inlet, a pump, connections in parallel from the radiator outlet to the jacket and the pump, and a nozzle in the housing adapted to be supplied by the pump.

11. In a cooling system for motor vehicles, a radiator, a cooling jacket connected to the radiator to form a closed system, a nozzle in the connection between the jacket and the radiator inlet, and a pump in parallel with the jacket and connected to the nozzle to exert an ejector action on said jacket.

12. In a cooling system for motor vehicles, a radiator, a cooling jacket in series therewith to form a closed system, and a pump in series with the radiator and in parallel with the jackets adapted to increase the flow through the radiator.

In testimony whereof I affix my signature.

ALFRED MOORHOUSE.
